UNITED STATES PATENT OFFICE

2,158,876

LUBRICATING DEVICE

John O. Lewis, Wesleyville, Pa., assignor to General Electric Company, a corporation of New York

Application August 12, 1937, Serial No. 158,724

6 Claims. (Cl. 308—132)

My invention relates to oil reservoir bearing lubricating devices of the type employing a storage reservoir in which lubricant is contained below atmospheric pressure above an outlet formed in the lower part thereof, and from which the flow of oil is regulated by the admission of air to the upper portion of the reservoir.

An object of my invention is to provide an improved and simplified lubricating device of the type above set forth.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, the single figure is an electric motor end shield showing in cross section a bearing and lubricating device embodying my invention.

Referring to the drawing, I have shown an electric motor end shield 1 provided with a bearing 2 in which a shaft 3 is journaled. Lubricant is fed to the bearing 2 from a pocket 4 formed at one side of the bearing and communicating therewith by a side opening 5. The pocket 4 also has a pair of openings 6 and 7 below the opening 5 and adjacent the bottom thereof, which communicates with a feeding chamber 8 arranged below the opening 5. Oil is fed to the bearing 2 at a uniform rate from a substantially constant level in the feeding chamber 8 by the capillary action of an absorbent material 9 contained in the pocket 4. In order to exclude dust and dirt from the pocket 4 and afford access thereto, a cover 10 is hinged at 11 to the top of the pocket, and the pocket is provided with a vent opening 12 therein, so that the air pressure in the pocket 4 will remain at substantially atmospheric pressure. The air in the feeding chamber 8 also is maintained at substantially atmospheric pressure by the filtration of air through the absorbent material 9 and through a vent tube 13 secured to the side of the pocket 4 and having a passage therethrough communicating with the top of the pocket near the vent opening 12 and with the bottom of the pocket adjacent the opening 6 and through the opening 6 into the feeding chamber 8.

Lubricant is fed to the chamber 8 from a reservoir 14 through an opening at the lower end of the reservoir, and the upper end of the reservoir is sealed and adapted to contain lubricant with air above the same at less than atmospheric pres-

sure. A vent tube 15 is screwed into a threaded opening 16 in the bottom of the reservoir 14 and is arranged with the upper end of the vent passage near the top of the reservoir 14 and the lower end thereof is provided with a restricted opening 17 which extends into the feeding chamber 8 at the desired normal level of lubricant therein. This vent tube arrangement controls the passage of air from the chamber 8 to the reservoir 14 through the vent tube 15 and the flow of lubricant from the reservoir to the feeding chamber. A filling tube 18 is screwed into a threaded opening 19 formed in the wall between the reservoir 14 and the feeding chamber 8 and extends through an opening 20 in the top of the reservoir and is welded thereto at 21. A cover 22 is hinged to the top of the filling tube to exclude dust and dirt therefrom during normal operation. The lower end of the filling tube is formed with a tapered conical finished inner surface 23 and openings 24 are formed in the filling tube adjacent the lower end thereof intermediate the ends of the tapered surface and at a lower level than the opening 17 in the vent tube, so as to be sealed by lubricant and prevent the passage of air from the filling tube to the reservoir. These openings provide communication between the reservoir and the filling tube, and an opening 25 formed in the lower end of the filling tube provides communication between the filling tube and the feeding chamber, thereby providing a direct communication between the reservoir 14 and the feeding chamber 8 through the openings 24 and 25.

Thus, when lubricant is fed to the bearing, the level in the feeding chamber drops and exposes the restricted vent tube opening 17, admitting air into the top of the reservoir 14 through the vent tube. This causes a flow of lubricant from the reservoir through the openings 24 into the filling tube and through the opening 25 into the feeding chamber 8. The resultant rise of lubricant in the feeding chamber continues until the opening 17 in the lower end of the vent tube is closed, thus preventing further admission of air into the reservoir, and the flow of lubricant therefrom ceases when the pressure due to the air and the lubricant in the reservoir equals atmospheric pressure. In this manner, the oil level in the feeding chamber is maintained at a substantially constant level at all times.

When it becomes necessary to fill the reservoir, a filling nozzle 26 is introduced through the filling tube 18, and a complementary tapered conical finished surface 27 at the end thereof pro-

vides a sealing fit with the conical surface 23 of the filling tube, and the end 28 of the nozzle is closed and fits into the opening 25 and provides a seal therewith. Openings 29 are formed 5 through the filling nozzle intermediate the ends of the tapered portion 27, and when the nozzle is fully inserted into the filling tube, these openings communicate with the reservoir 14 through the openings 24 in the filling tube for directing 10 the lubricant from the filling nozzle into the reservoir, and the seal between the nozzle and the filling tube about these openings prevents the flow of oil from either end of the filling tube or into the feeding chamber. When the reservoir is full, 15 lubricant overflows through the vent tube 15 and the increased resistance offered to the flow of lubricant through the restricted passage 17 will cause a decreased rate of flow of lubricant, and the pressure within the reservoir will be increased. 20 A pressure gauge 30 is connected to the filling nozzle 26 and arranged to indicate the increase in pressure in the reservoir, and thereby indicate to the operator that the level of lubricant in the reservoir is at the upper end of the vent tube 25 15 and that the lubricant supply should be cut off. By this arrangement, it is possible to prevent an excess of lubricant supply to the reservoir which would flow through the vent tube and flood the bearing.

30 While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by 40 Letters Patent of the United States, is:

1. A lubricating device for a bearing comprising a storage reservoir adapted to contain lubricant below atmospheric pressure, a feeding chamber arranged to feed lubricant from said reservoir 45 to the bearing, an opening providing direct communication between said storage reservoir and said feeding chamber, means having an opening at each end thereof and an intermediate opening communicating with said storage reservoir 50 for providing a filling passage for said reservoir, means adapted to communicate with said reservoir through the intermediate opening in said filling passage for supplying lubricant to said reservoir and adapted to provide a seal with said reservoir filling passage for preventing the flow 55 of lubricant from either end of said filling passage during filling of said reservoir, and means associated with said filling means for indicating the level of lubricant in said reservoir.

60 2. A lubricating device for a bearing comprising a storage reservoir adapted to contain lubricant below atmospheric pressure, a feeding chamber arranged to feed lubricant from said reservoir to the bearing, an opening providing direct 65 communication between said storage reservoir and said feeding chamber, a filling tube secured in said opening having an opening at each end thereof and an opening communicating with said storage reservoir, one of said end openings communicating with said feeding chamber, and means including an adjustable vent between said reservoir and said feeding chamber having an opening adapted to communicate with said storage reservoir and another restricted opening 70 75 communicating with said feeding chamber for

regulating the flow of lubricant to said bearing.

3. A lubricating device for a bearing comprising a storage reservoir adapted to contain lubricant below atmospheric pressure, a feeding chamber arranged to feed lubricant from said reservoir to the bearing, an opening providing direct communication between said storage reservoir and said feeding chamber, a filling tube secured in said opening having an opening at each end thereof and an opening communicating with said storage reservoir, one of said end openings communicating with said feeding chamber, means having an opening adapted to communicate with said storage reservoir through said filling tube opening communicating with said reservoir for supplying lubricant to said reservoir and adapted to provide a lubricant seal with said filling tube for preventing the flow of lubricant from the openings at the ends of said filling tube during filling of said reservoir, said reservoir having a vent passage communicating with said reservoir and with said feeding chamber arranged to control the admission of air to said reservoir and the flow of lubricant therefrom, said vent passage providing for the escape of air from said reservoir during filling and being sufficiently restricted to cause a rise in pressure in said reservoir upon flow of lubricant through said restriction during filling of said reservoir, and means responsive to the rise in pressure in said reservoir upon the flow of lubricant through said restriction during filling for indicating the level of lubricant in said reservoir.

4. A lubricating device for a bearing comprising a storage reservoir adapted to contain lubricant below atmospheric pressure, a feeding chamber arranged to feed lubricant from said reservoir to the bearing, a pocket opening to the bearing and communicating with said feeding chamber, said pocket having a vent passage communicating with the upper end thereof and with the lower end thereof adjacent said feeding chamber to provide substantially atmospheric pressure in said feeding chamber, absorbent material in said pocket arranged to feed lubricant therefrom to the bearing, an opening providing a direct communication between said storage reservoir and said feeding chamber, a filling tube having an opening at each end thereof and an intermediate opening and being secured in said opening communicating with said feeding chamber and with said storage reservoir, and means adapted to communicate with said storage reservoir through said filling tube for supplying lubricant to said reservoir and adapted to provide a lubricant seal with said filling tube for preventing the flow of lubricant from either end opening of said filling tube during filling of said reservoir.

5. A lubricating device for a bearing comprising a storage reservoir adapted to contain lubricant below atmospheric pressure, a feeding chamber arranged to feed lubricant from said reservoir to the bearing, a pocket opening to the bearing and communicating with said feeding chamber, said pocket having a vent passage communicating with the upper end thereof and with the lower end thereof adjacent said feeding chamber to provide substantially atmospheric pressure in said feeding chamber, absorbent material in said pocket arranged to feed lubricant therefrom to the bearing, an opening providing direct communication between said storage reservoir and said feeding chamber, a filling tube having an opening at each end thereof and an

intermediate opening and being secured in said opening and communicating with said feeding chamber and with said storage reservoir, means having an opening communicating with said storage reservoir through said filling tube for supplying lubricant to said reservoir and providing a lubricant seal with said filling tube for preventing the flow of lubricant from either end opening of said filling tube during filling of said reservoir, and means including a vent tube communicating with said reservoir and with said feeding chamber for controlling the admission of air to said reservoir and the flow of lubricant therefrom, said vent tube being adjustably secured to said reservoir and said feeding chamber to provide for adjustment of normal lubricant level in said feeding chamber.

6. A lubricating device for a bearing comprising a storage reservoir adapted to contain lubricant below atmospheric pressure, a feeding chamber arranged to feed lubricant from said reservoir to the bearing, a pocket opening to the bearing and communicating with said feeding chamber, said pocket having a vent passage communicating with the upper end thereof and with the lower end thereof adjacent said feeding chamber to provide substantially atmospheric pressure in said feeding chamber, absorbent material

in said pocket arranged to feed lubricant therefrom to the bearing, an opening providing a direct communication between said storage reservoir and said feeding chamber, means providing a filling passage having an opening at each end thereof and an intermediate opening communicating with said storage reservoir for providing a filling passage for said reservoir, means adapted to communicate with said reservoir through said filling passage for supplying lubricant to said reservoir and adapted to provide a seal with said filling passage for preventing the flow of lubricant from either end opening of said filling passage during filling of said reservoir, said reservoir having a vent passage communicating with said reservoir and with said feeding chamber arranged to control the admission of air to said reservoir and the flow of lubricant therefrom, said vent passage providing for the escape of air from said reservoir during filling and being sufficiently restricted to cause a rise in pressure in said reservoir upon flow of lubricant through said restriction during filling of said reservoir, and means responsive to the rise in pressure in said reservoir upon the flow of lubricant through said restriction during filling for indicating the level of lubricant in said reservoir.

JOHN O. LEWIS.
